UNITED STATES PATENT OFFICE.

FREDERICK P. FISCHER, OF CHICAGO, ILLINOIS.

SMOKE CONSUMER.

Application filed May 13, 1921. Serial No. 469,151.

To all whom it may concern:

Be it known that I, FREDERICK P. FISCHER, a citizen of the United States, and a resident of the city of Chicago, county of Cook, 5 and State of Illinois, have invented certain new and useful Improvements in Smoke Consumers, of which the following is a specification.

My invention relates to improvements in 10 smoke consumers and has for its main object the provision of means to burn all carbons and heavy gases passing from the combustion chamber of a boiler to the smoke stack and to prevent them from escaping 15 through said stack to the atmosphere.

Another object is to provide means to warm fresh air by the use of heated furnace smoke and gases and forcibly feed such heated air to the fire through the grate.

20 Other objects will appear hereinafter.

The invention consists in the combinations and arrangements of parts hereinafter described and claimed.

The invention will be best understood by 25 reference to the accompanying drawings forming a part of this specification, and in which,

Fig. 1 is a side elevation of my invention applied to a boiler, portions of the figure 30 being broken away;

Fig. 2 is an enlarged fragmentary view showing the regulating valve, being in part a section on line 2—2 of Fig. 1;

Fig. 3 is an enlarged sectional view of 35 the safety valve taken on line 3—3 of Fig. 4;

Fig. 4 is a top plan view of parts shown in Fig. 1; and,

Fig. 5 is a front view thereof, partly in section.

40 In the form illustrated, my invention is shown applied to an ordinary fire-box boiler 10 provided with a grate 11 and a space or chamber 12 forming the usual ash box, beneath the grate. A smoke pipe 13 connects the usual smoke chamber or smoke box of 45 the boiler with the smoke stack 14. All of the above is well known construction.

In the usual operation of the boiler or 50 furnace, especially where bituminous coal is consumed improper and incomplete combustion frequently takes place, and particles of finely divided carbon containing inflammable gases escape from the smoke stack in the form of heavy, black smoke, which 55 entails a loss of fuel and also becomes a troublesome nuisance. I prevent such loss

of fuel value and avoid the smoke nuisance, and at the same time provide a force draft with the following construction.

A conduit 15 is connected with the smoke 60 pipe 13, communicating with the interior thereof, and is provided with a fresh air duct or inlet pipe 16 near said connection, forming a Y with said conduit. A valve 17 is mounted in the junction of air pipe and 65 conduit, as best shown in Fig. 2, and is provided with a handle 18 whereby the valve may be swung into either fork of the Y and the effective cross-section of either the air pipe or the conduit may be varied and 70 the admission of air through the air pipe or of gas from the smoke pipe through the conduit may be regulated. The conduit extends over the boiler to the front portion thereof and descends in two branches 20 75 and 21, each communicating at one side with the chamber 12 beneath the grate. A safety valve 19 is provided for said conduit, being mounted thereon at any convenient point. If desired, only one vertical conduit may 80 be used and connected with the chamber 12 near the front center thereof.

A fan 22 is mounted in a casing 23 interposed in said conduit adjacent the forward end of the boiler and over a floor 24 85 which is located immediately above the boiler and beneath the smoke pipe 13 and the horizontal portion of conduit 15, as best shown in Fig. 1. A pulley 25 is mounted on the outer end of the fan shaft 26 90 which is rotatably mounted in the fan casing and operates the fan, said pulley being operated by a belt 27 which may be driven by any suitable power supplying member (not shown).

95 While I have illustrated and described the preferred form of construction for carrying my invention into effect, this is capable of variation and modification without departing from the spirit of the invention. I, 100 therefore, do not wish to be limited to the precise details of the construction set forth, but desire to avail myself of such variations and modifications as come within the scope 105 of the appended claims.

Having described my invention, what I 110 claim is new and desire to secure by Letters Patent, is:—

1. In combination with a boiler provided with a grate and chamber beneath said grate and with a smoke pipe connecting said boiler with a nearby smoke stack, a conduit extend-

ing along the front and the top of said boiler and connecting the front end of said chamber with said smoke pipe, an air inlet duct connected with the said conduit, adjacent 5 said smoke pipe, means interposed in said conduit for forcing carbon and gas from said pipe and air from said duct through the grate, and a single valve to regulate the proportionate amount of carbon and of air to be admitted to said chamber.

2. In combination with a boiler provided with a grate and an ash pit beneath said grate and with a pipe connecting said boiler 15 with the smoke stack, a Y-shaped conduit having one fork connecting with said pipe and the other fork forming an air inlet, the stem of said conduit extending over said boiler and communicating with said ash pit, 20 a control valve at the junction of said forks, means mounted in the front of said stem for forcing a current from said pipe and inlet to said pit, and a safety valve interposed in said conduit.

3. In combination with a stationary boiler 25 provided with a grate and chamber beneath said grate and with a smoke pipe connecting said boiler with a smoke stack adjacent said boiler, a conduit having two branches opening through the front wall of 30 said chamber adjacent each side thereof and a stem communicating with said pipe, a fresh air duct connected with said conduit adjacent said smoke pipe to warm the air with the smoke pipe gases before entering said 35 chamber, a fan mounted in said conduit at the junction of said branches for feeding fresh air from said duct and heated gases and carbon from said pipe through said grate, and means for regulating the intake 40 of air and gases.

In testimony whereof I have signed my name to this specification in the presence of two subscribing witnesses.

FREDERICK P. FISCHER.
